UNITED STATES PATENT OFFICE.

FRED A. BABCOCK, OF WYNDMOOR, PENNSYLVANIA.

BLAST-NOZZLE.

992,144.

Specification of Letters Patent. Patented May 16, 1911.

Application filed October 21, 1910. Serial No. 588,338.

To all whom it may concern:

Be it known that I, FRED A. BABCOCK, a citizen of the United States, residing at Wyndmoor, county of Montgomery, State 5 of Pennsylvania, have invented a new and useful Blast-Nozzle, of which the following is a specification.

My invention consists of a suction-nozzle or blast-nozzle in which the actuated medium is axially introduced and the actuating medium introduced in an annular jet surrounding the column or jet of the actuated medium.

It further consists of such a nozzle in 15 which the jet of the actuating medium is controlled by adjustment of the tube conveying the actuated medium.

It further consists of improved means for creating the annular actuating et.

20 It further consists of improved means for renewing the jet tube when worn or broken.

It further consists of other novel details of construction, all as will be hereinafter fully set forth.

25 For the purpose of illustrating my invention, I have shown in the accompanying drawings, one form thereof which is at present preferred by me, since the same has been found in practice to give satisfactory and 30 reliable results, although it is to be understood that the various instrumentalities of which my invention consists can be variously arranged and organized and that my invention is not limited to the precise arrangement and organization of instrumentalities as herein shown and described.

Figure 1 represents an axial section of my improved blast-nozzle. Fig. 2 represents a face view of the baffle-plate or dia- 40 phragm in the blast-chamber.

Similar numerals of reference indicate corresponding parts in the figures.

Referring to the drawings: The device embodying my invention may be employed 45 for the purpose of creating a jet or spray of any fluid, gas, steam granulated or pulverized substance by means of a fluid under pressure, but it is particularly designed to create a sand-blast by means of compressed 50 air as the actuating medium, for the various purposes for which such sand-blast is used. It must therefore be understood that whenever the words "air" or "sand" are used in the following description, such terms are 55 merely employed for convenience sake and refer, respectively, to the "actuating me-

dium" and the "actuated medium" irrespective of whatever said media may be.

The device has a casing composed of two parts, 1 and 2, of preferably conical outlines, 60 with the cones placed base to base, and formed with conical communicating chambers, 3 and 4, in their interiors, both forming a blast-chamber. The rear part 1 of the casing has an externally screw threaded 65 forward end, 5, upon which an internal screw thread, 6, in the rear of the forward part 2 is screwed,—a groove, 7, being formed at this joint, into which the suitable portion of a baffle-plate or perforated dia- 70 phragm, 8, is clamped. This baffle-plate has an annular passage formed by a series of openings, 9. A blast-inlet pipe, 10, for the actuating medium,—compressed air from a compressor and reservoir,—is suit- 75 ably secured (by screwthreads) into the rear of the rear conical chamber. A supply-pipe, 11, is screw threaded in the rear wall of the rear part of the casing to extend axially through the two blast chambers and through 80 a central opening, 12, in the baffle-plate and has a lock-nut, 13, upon it for locking it in its adjusted position. The end 14, of the supply-pipe is beveled or tapering to form a valve which corresponds to a beveled or 85 tapering valve-seat, 15, with which the casing is provided, preferably at the forward end of the forward conical chamber. A washer, 16, bears against the forward face of the seat and a mingling-chamber is 90 formed in a jet-tube, 17, having its inner end screwed into the forward end of the forward chamber, and inclosing a lining tube, 18, which is clamped with its inner end against the washer by a shoulder, 19, 95 within the jet-tube, bearing against the outer end of the lining-tube.

In practice, the pipe for the actuating medium (the blast-pipe 10) is connected to a source of fluid under pressure (compressed air,) and the supply-pipe for the actuated medium (sand) is connected to a suitable supply reservoir. When the blast is started, the air enters the rear chamber and fills the same, whereupon it passes into the front 100 chamber through the annular passage in the baffle-plate. As said passage is annularly arranged, the air-blast will be evenly distributed in the front chamber and around the supply-pipe, notwithstanding the blast- 105 pipe entering the side of the rear chamber. The air-current in the front chamber con-

tracts at the forward end of said chamber and issues in a tubular jet around the mouth of the supply-pipe, creating a vacuum which draws the sand from the same, whereupon 5 the jet of mixed sand and air passes through the jet-tube and issues at the mouth of the same.

The air-blast at the mouth of the supply-pipe may be adjusted according to requirements or desire, by screwing the valve-end 10 of the supply-pipe closer to or farther from its seat to decrease or increase the blast opening. When the supply-pipe is properly adjusted to give the proper blast-opening, the 15 lock-nut is tightened to secure the pipe in its adjusted position. The valve-seat may be, in the construction here shown and preferably employed, moved and adjusted by removing the jet-tube and the washer, and the 20 lining-tube of the mingling-chamber within the jet-tube, which wears out frequently on account of its exposure to the full strength of the sand-blast, may be renewed by unscrewing the jet-tube, inserting a new lining-tube and again screwing the jet-tube in 25 place.

By forming the rear chamber conical and rearwardly tapering and having the blast pipe entering it in a forwardly oblique direction, the blast passing around the supply-pipe will be forwardly deflected, and guided toward the annular passage through the baffle-plate.

By placing the supply-pipe for the actuated medium axially within the jet of the actuating medium, the supply of the actuated medium will have a straight path through said pipe and the entire device, whereby clogging of a pulverized or granulated medium such as sand, in said pipe will be avoided, and the entire supply-pipe and jet-tube will furnish a direct and axially aligned duct.

By forwardly tapering the forward chamber and making the parallel faces of the seat and the end of the supply-pipe at an angle to such taper, to cause a comparatively abrupt convergence of the annular blast opening and of the blast of the actuating medium in its relation to the end of the supply pipe, the vacuum formed by the air-blast will be close to the end of the supply-pipe and thus exercise greater suction than if such blast opening had a longer and more gradual taper, and the surface friction for the converging annular air-blast against the sides of the comparatively short blast-opening will be less than in an opening of long taper. The valve-seat may be renewed by 55 simply unscrewing the jet-tube, removing the washer and seat, inserting a new seat and replacing the washer and tube, without disturbing any other parts of the device.

While I have described the pipe 10 as the 60 blast inlet pipe and the pipe 11 as the sup-

ply pipe, I desire it understood that under some conditions the air may be passed through pipe 11 thus serving as an inlet while the pipe 10 may serve as the supply pipe. For example, I may employ a nozzle 70 for use in spraying plants in which event I may employ a gas or fluid which I may desire to mix with air and conducting the gas or fluid through pipe 10 while the air is passed through pipe 11. I further desire it 75 understood that any form of discharge opening for the jet tube 17 may be employed, as in some instances I may desire the discharge end to be provided with a slot or plurality of openings, in order to form the spray 80 85 which may be employed.

Having thus described my invention, what I claim as new and desire to secure by Letters Patent, is:—

1. In a device of the character stated, a 85 casing having inlet for the actuating fluid and having a forwardly tapering chamber and a valve-seat at the end of said chamber and at an abrupt angle to the taper of the same, and a supply-pipe axially within said 90 chamber and having its forward end beveled at the same angle as the seat to form with it an annular abruptly converging blast-opening, whereby the vacuum is created closely in front of the mouth of the supply pipe.

2. In a device of the character stated, a 100 casing having inlet for the actuating fluid and having a forwardly tapering chamber and a valve-seat at the end of said chamber and at an abrupt angle to the taper of the same, a supply-pipe axially within said 105 chamber and having its forward end beveled at the same angle as the seat to form with it an annular abruptly converging blast-opening and a jet tube secured in the forward end of the casing and in axial alignment with the supply-pipe, whereby the 110 vacuum is created closely in front of the mouth of the supply-pipe and the jet directed by the tube.

3. In a device of the character stated, a 115 casing having a forwardly tapering chamber having inlet for the actuating fluid, a valve-seat removably secured in an opening in the apex of such chamber and having its seat surface at an abrupt angle to the taper of the same, a supply-pipe axially within said chamber and having its end beveled at the same angle as the seat to form with it 120 an annular abruptly converging blast-opening, and a jet-tube projecting from the forward end of the blast-tube in axial alignment with the supply-tube.

4. In a device of the character stated, a 125 casing composed of two tapering parts having tapering chambers within them and secured together at their wider ends, an annular baffle-plate clamped between the wide ends of the chambers and formed with an 130

- annular series of openings, a blast-supply pipe secured forwardly oblique in the rear chamber, a valve-seat in the apex of the forward chamber and having its seat surface at an abrupt angle to the taper of the walls of the chamber, a supply-pipe axially supported through the chambers and baffle-plate and having its forward end beveled at the same angle as the seat to form with it an annular abruptly converging blast-opening, 10 and a jet-tube projecting from the forward end of the blast-tube in axial alinement with the supply-tube.
